UNITED STATES PATENT OFFICE.

JOSEPH HOFFMAN, OF NEW YORK, N. Y., ASSIGNOR TO JOSEPH RECKEN-DORFER, OF SAME PLACE.

LEAD AND CRAYON HOLDER.

SPECIFICATION forming part of Letters Patent No. 237,531, dated February 8, 1881.

Application filed August 28, 1880. (Model.)

To all whom it may concern:

Be it known that I, JOSEPH HOFFMAN, of the city, county, and State of New York, have invented certain new and useful Improvements 5 in Lead and Crayon Holders, of which the following is a specification.

My invention has reference to that kind of lead and crayon holders known as the "automatic holder"—a holder in which the jaws are 10 by the action of a spring caused to close upon the lead, and are caused to open by pressure exerted by hand against the stress of the spring.

My invention consists in combining with the 15 longitudinally-movable lead-containing tube or receiver and its inclosing case or handle jaws attached to and carried by the tube, and provided with side lips or flanges which enter V-shaped or equivalently-formed grooves or 20 slots in the case or handle, whereby the jaws, when moved in one direction, will be caused to close on and grasp the lead, and when moved in the other direction will be permitted to open or release their hold on the lead.

25 The nature of my invention and the manner in which the same is or may be carried into effect will be understood by reference to the accompanying drawings, in which—

Figure 1 is a perspective view of a holder 30 embodying my invention. Fig. 2 is a vertical central section of the same. Fig. 3 is a perspective view of the front or nozzle end of the holder enlarged. Fig. 4 is a like view of the front portion of the lead receiver or tube, together with the jaws carried by it.

A is the tubular case or handle, terminating in the usual tapering or contracted nozzle or front end, a. B is the lead tube or receiver, inclosed by and longitudinally movable with 40 respect to the handle. C is the external cap, attached to the tube and fitting the rear end of the handle. b is the spring between the cap and the handle, which serves to retract the tube so as to hold the jaws in a normally-closed position, the tube being pushed forward 45 against the stress of the spring by pressing on the cap C. The rearward movement of the tube may be limited by the customary device employed for that purpose in my automatic pencil-holder now in the market; or, the jaws 50 constructed and combined with the tube and

handle, as I am about to describe, will serve that purpose.

The parts thus far described are substantially like those found in the now well-known 55 "automatic holder," of which the holder shown in my Letters Patent No. 215,521, dated May 29, 1879, (reissued in two divisions, Nos. 8,967 and 8,968, November 18, 1879,) is the type.

In lieu, however, of having jaws which are 60 formed with inclined surfaces acted on by the case or handle to cause them to close together, I now attach to or otherwise form upon the front end of the lead receiver or tube B jaws D, which have no such inclines, but are provided with side lips, flanges, or their equivalent, e, which enter and engage slots d in the nozzle a of the case. These slots, as shown, 65 are of V form—that is to say, they are widest at the front, and thence taper or contract rearwardly.

The spring b tends to pull back the tube B, and consequently the jaws carried by the tube are also drawn back; but by this movement of the jaws the lips e are brought into the narrowing portions of the slots d, and are consequently drawn together, thus closing the jaws and causing them to grasp the lead e, as shown in Fig. 1. When, however, the cap C is pressed forward the jaws will thereby be moved 75 forward, bringing their lips e into the wider portions of the slots d, and thus permitting the jaws to release their hold on the lead. The jaws shown in the drawings are made of spring sheet metal, and normally stand apart; but 80 they may be otherwise made, if desired.

In lieu of slots, the nozzle a may have grooves, and these grooves, of a wedge-like or tapering form, may indeed be formed in or on any suitable portion of the interior of the front end of 85 the handle.

While I prefer to use two grooves or slots and two pairs of lips or flanges, yet one groove and one pair of lips alone may be employed, in which case the part which grasps the lead 90 may be in the form of an expandible tube split on one side, with lips or flanges on the two edges of the split to engage the tapering groove or slot in the handle.

What I claim, and desire to secure by Letters Patent, is—

1. A lead or crayon holder in which the case

or handle is combined with longitudinally-movable expansible lead-holding jaws, provided on contiguous edges with laterally-projecting lips which enter and engage one or more wedge-like or tapering slots or their equivalent in the case, substantially as and for the purposes set forth.

2. The combination of the handle or case provided at its front end with wedge-like or tapering slots or their equivalent, as described, with the longitudinally-movable lead-containing tube or receiver, having at its front end grasping-jaws provided with lips or flanges which enter and engage the slotted or equivalently-formed part of the case or handle, substantially as and for the purposes hereinbefore set forth.

3. The combination, substantially as hereinbefore set forth, of the case or handle, formed at its front with tapering or wedge-like slots or their equivalent, the longitudinally-movable lead-containing tube, terminating in grasping-jaws provided with lips or flanges which enter and engage the said slotted or equivalently-formed portion of the case, the pressure-
cap, and the retracting-spring.

In testimony whereof I have hereunto set my hand this 20th day of August, A. D. 1880.

JOSEPH HOFFMAN.
